WITNESS:

UNITED STATES PATENT OFFICE

1,956,504

WINDOW SHADE, CURTAIN, AND DRAPERY HOLDER

Luther V. Hank, Arnold, Pa., assignor of one-sixth to Minotti Giudice, one-sixth to Salvatore Tamburo, one-sixth to Domenico Verteramo, all of New Kensington, Pa., one-sixth to Antonio Saulle and one-sixth to Sabatius Patesta, both of Arnold, Pa.

Application August 22, 1933, Serial No. 686,281

1 Claim. (Cl. 156—24)

The invention relates to a shade, curtain and drapery holder and more especially to a self-fastening bracket.

The primary object of the invention is the provision of an article of this character, wherein the same is preferably formed from a wire bent into the required form or shape to serve as a shade, curtain and drapery holder, and one end of said wire is pointed and threaded so that it can be fastened in place upon a window frame, thereby eliminating the necessity for separate fasteners for the mounting of the article.

Another object of the invention is the provision of an article of this character, which is simple in construction, thoroughly reliable and efficient in its purpose, strong, durable, readily and easily applied and removed from a window frame, and inexpensive to manufacture.

With these and other objects in view, the invention consists in the features of construction, combination and arrangement of parts as will be hereinafter more fully described in detail, illustrated in the accompanying drawing, which discloses the preferred embodiment of the invention, and pointed out in the claim hereunto appended.

In the accompanying drawing:

Figure 1 is an elevation of a pair of brackets constructed in accordance with the invention and in position for the hanging of a shade, drapery and a curtain.

Figure 2 is a top plan view showing one of the brackets fastened to the window frame, the latter being in section, and by dotted lines is illustrated the shade and rods for draperies and curtains.

Figure 3 is a side elevation of one of the brackets.

Figure 4 is a perspective view thereof.

Figure 5 is a view similar to Figure 4 showing the companion bracket for the one disclosed in Figure 4.

Figure 6 is a perspective view of a slight modified form.

Similar reference characters indicate corresponding parts throughout the several views in the drawing.

Referring to the drawing in detail, A and B designate a pair of brackets, respectively, these being constructed in accordance with the invention and each is formed from a wire length bent on itself to provide a contact loop 10 with an outwardly directed arm 11 at one side thereof and an inwardly directed pointed threaded fastening terminal 12 at the opposite side of said loop, this terminal 12 being adapted to be screwed into the window frame for the mounting of the bracket.

The arm 11 of the bracket A is bent to provide a depending yoke 13 constituting an open notch 14 for the trunnion 15 of a window shade roller 16, while the arm 11 of the bracket B is bent to provide a depending eye 17 for receiving the other 60 trunnion 18 of said shade roller 16, as will be clearly apparent in Figure 1 of the drawing.

The arm 11 of each bracket A and B is bent outwardly and inwardly to provide an extension 19 having a perpendicular upturned post 20 for the 65 detachable mounting thereon of a curtain rod 21, as is shown in Figure 2 of the drawing.

The extension 19 next to the post 20 has joined therewith a branch extension 22 at its outer side and this branch extension is bent laterally at 23 70 and then upwardly perpendicularly to form a supplemental post 24 for the detachable connection therewith of a drapery rod 25.

In Figure 6 of the drawing there is shown a slight modification, wherein the bracket C, which 75 is alike to either of the brackets A and B, has the extension 26 provided with an upstanding perpendicular single post 27.

In the mounting of the brackets A, B and C the pointed threaded end 12 is screwed into place in 80 the window frame D, it being understood, of course, that a pair of the brackets are employed for the mounting of the window shade roller 16 which is of standard type and the depending loop 10 will abut the said window frame to maintain 85 the bracket straight with the arm 11 at right angles thereto.

The curtain and drapery rods 21 and 25 are fastened in place on the bracket as hereinbefore set forth.

What is claimed is:

A bracket of the character described formed from a single length of wire to provide a straight arm having a depending loop and yoke spaced from each other, one end of the wire being pointed 95 and threaded to provide a fastening terminal, a laterally and inwardly bent extension on said arm, means formed from the extension for the detachable fastening of a drapery or curtain rod therewith, and a supplemental extension joined 100 with the first-named extension and having means for the connection of a second drapery or curtain rod therewith.

LUTHER V. HANK.
